CHARLES A. DILLON, OF CANTON, OHIO, ASSIGNOR TO THE UNITED ELECTRIC COMPANY, OF CANTON, OHIO, A CORPORATION OF OHIO.

KEY-PLUG.

1,137,466.

Specification of Letters Patent. Patented Apr. 27, 1915.

Application filed June 18, 1913. Serial No. 774,490.

To all whom it may concern:

Be it known that I, CHARLES A. DILLON, a citizen of the United States, residing at Canton, in the county of Stark and State of Ohio, have invented certain new and useful 5 Improvements in Key-Plugs, of which the following is a specification.

The invention relates to plugs for closing 10 inlet openings and orifices of pipes, and other parts of suction cleaning apparatus; and the object of the improvement is to provide an efficient and durable plug having a 15 resilient body portion with a head portion which will not be mutilated or deformed by the key which is usually employed as a handle 20 for inserting and removing the plug into and from the opening. This object is attained by making the plug of rubber with a hollow cylindric body portion and providing 25 metallic disk and socket plates in the head portion with a metallic face plate thereon and an intervening hard spacing plate.

A preferred embodiment of the invention 30 thus set forth in general terms, is illustrated 25 in the accompanying drawing forming part hereof, in which—

Figure 1, is a fragmentary perspective 35 view of a baseboard showing the face of the improved plug therein and a key located adjacent to the key hole; Fig. 2, a perspective view of the body plate and the socket plate 40 in position for assembling; Fig. 3, a similar view showing the same plates assembled and clamped together; Fig. 4, is an inner side 45 perspective view showing the rubber portion of the plug; Fig. 5, an outer side perspective view of the rubber portion of the plug showing the spacing plate recess; Fig. 6, a detached perspective view of the spacing plate; Fig. 7, a detached perspective 50 view of the face plate; Fig. 8, a section of the completed plug; and, Fig. 9, a fragmentary section of an inlet pipe in a base board with a finishing ring thereon, showing 55 the improved plug in side elevation therein.

Similar numerals refer to similar parts throughout the drawings.

The head plate 1 is preferably made of 60 sheet or malleable metal in the form of a flat disk having the central key hole 2 formed therein, and a plurality of tongues 3^a cut and bent inward from the peripheral portion thereof forming a plurality of peripheral notches 3^a. The socket plate 4 is likewise 65 preferably made of sheet metal in the form

of a spherical cup with the peripheral flange 5 thereon which is entered inside the tongues 3^a of the body plate. The tongues 3^a are clamped around the peripheral flange 5 to securely hold the socket plate in position, as 70 shown in Fig. 3. The rubber portion of the plug is then formed or molded upon and around the head and socket plates in the usual manner well known in the art. The rubber is shaped to form the cylindric body 75 portion 6 of the plug and the coating or layer 7 on the outer side, the layer 8 on the inner side and the rim 9 around the peripheral portions of the head and socket plates.

It is evident that the entrance of the rubber 80 into the peripheral notches 3^a of the head plate and its engagement around the peripheral flange 5 of the socket plate and the clamping tongues 3^a of the head plate, serves to securely hold the rubber upon these 85 parts. The recess 10 is formed in the rubber layer 7 on the outer side of the head plate around the key hole 2 therein, into which recess is fitted the spacing plate 11 having the key hole 2^a therein corresponding 90 to the key hole in the head plate, which spacing plate 11 is made of hard material and of a thickness corresponding to the normal thickness of the rubber layer 7 on the outer side of the body plate.

The face plate 12 of the plug is made of 95 thin sheet metal suitably finished on its outer side and provided with the inturned rim flange 13 which is fitted around and clamped upon the rim portion 9 of the rubber portion of the head of the plug, as shown in Figs. 8 and 9. The central key hole 2^b is provided in the face plate, corresponding to the key holes 2 and 2^a in the head and spacing plates, and it is evident 100 that the presence of the hard spacing plate serves to sustain that portion of the face plate around the key hole from being bent inward or otherwise deformed by the insertion of the tangs 14 of the key 15. Furthermore the formation of the key hole in the several hard or metallic plates prevents the edges thereof from being mutilated. It is also evident that when the tangs of the key are inserted through the key hole into 105 the socket 16 formed by the metallic plates embedded in the head of the plug, these plates prevent the mutilation of the rubber portions of the plug by the manipulation of the key. And finally, the hollow-cylindric 110

dric rubber body portion 6 of the plug is preferably made with the well defined annular enlargement or rib 18 at or near the free rim 18 thereof, the circumference of which rib is normally slightly larger than the wall 19 of the inlet opening or orifice, so that when the plug is entered into the orifice, the circumferential compression of the rib makes an air tight fit of the rim portion of the plug in the orifice.

10 I claim:

1. A key plug composed of rubber including a head portion and a hollow cylindric body portion having a free rim at its inner end, there being an annular rib around the body portion adjacent to the free rim thereof.

2. A key plug composed of rubber including a head portion with a metallic reinforcement therein and a hollow cylindric body portion having a free rim at its inner end, there being an annular rib around the body portion adjacent to the free rim thereof.

25 3. A key plug composed of rubber having

metallic disk and socket plates embedded in its head portion, there being a key socket formed by the socket plate on the inner side of the disk plate and a central key hole communicating with the socket.

30

4. A key plug composed of rubber having metallic disk and socket plates embedded in its head portion, and a metallic face plate on the outer side thereof, there being a key socket formed by the socket plate on the inner side of the disk plate, and a key hole through the disk and face plates.

35

5. A key plug composed of rubber having metallic disk and socket plates embedded in its head portion, a metallic face plate on the outer side thereof, and a spacing plate between the central portions of the disk and face plates, there being a key socket formed by the socket plate on the inner side of the disk plate and a key hole through the disk, 40 spacing and face plates.

45

CHARLES A. DILLON.
